CLAIM

The ornamental design for a mobile mount, as shown and described.

DESCRIPTION

FIG. 1 is a top, front and right perspective view of a mobile mount;

FIG. 2 is a front elevation view thereof;

FIG. 3 is a rear elevation view thereof;

FIG. 4 is a left side elevation view thereof, the right side elevation view being a mirror image thereof;

FIG. 5 is a bottom plan view thereof;

FIG. 6 is a top plan view thereof;

FIG. 7 is a front, bottom and left side perspective view thereof;

FIG. 8 is a rear and right side perspective view thereof; and,

FIG. 9 is an enlarged front, top and right side perspective view thereof.

The evenly-spaced broken lines shown in FIGS. 1, 6, 8 and 9 illustrate portions of the mobile mount that form no part of the claimed design. The dash-dot-dot broken lines shown in FIGS. 1-8 illustrate environment which forms no part of the claimed design.

1 Claim, 9 Drawing Sheets
